Patented Apr. 18, 1916.

THE COLUMBIA PLANOGRAPH CO., WASHINGTON, D. C.

UNITED STATES PATENT OFFICE.

FRANK H. FRY, OF STILTNER, WEST VIRGINIA.

DINING-TABLE.

1,179,909.

Specification of Letters Patent. Patented Apr. 18, 1916.

Application filed August 19, 1915. Serial No. 46,277.

To all whom it may concern:

Be it known that I, FRANK H. FRY, a citizen of the United States, residing at Stiltner, in the county of Wayne and State of West Virginia, have invented a new and useful Dining-Table; and I do hereby declare the following to be a full, clear, and exact description of the invention, such as will enable others skilled in the art to which it appertains to make and use the same.

This invention relates to an improved dining table, and an object of the invention is to provide an extensible table provided with a revolving center piece, designed to be rotated by the persons at the table, so that articles on one side of the center piece may be reached by persons on the opposite side.

Another object of the invention is to provide a revolving center piece having radial 20 sliding drawers to contain napkins and the like, and various eating utensils.

In practical fields the details of construction may necessitate alterations, falling within the scope of what is claimed.

25 The invention comprises further features and combination of parts, as hereinafter set forth, shown in the drawings and claimed.

In the drawings: Figure 1 is a view in side elevation of the improved table constructed in accordance with the invention. Fig. 2 is a plan view partly broken away and in section, showing the radial sliding drawers of the center piece. Fig. 3 is a sectional view on line 3—3 of Fig. 2. Fig. 4 is a plan view showing the table extended, and the revolving center piece removed. Fig. 5 is an enlarged detail view in section of the ball bearing and the attending parts of the revolving center piece. Fig. 6 is a 40 sectional view on line 6—6 of Fig. 4.

Referring more especially to the drawings, 1 designates the central column or standard of the table having the usual legs 2. Arranged on the upper end of the column is a plate 5 having central annular depressions 6. The opposite ends of the plate 5 have elongated tongues 7, to enter the grooves 8 upon the adjacent faces of the slide bars 9 of the extension section 10 of the table, so that when the extension section 10 of the table is extended as shown in Fig. 4, the tongues 7 will slide in said grooves 8. Upon the outer faces of the bars 9 are grooves 11, to receive the elongated tongue 55 12 of the bars 13 of the extension section 14 of the table, so that the extension section

may be extended slidably. Secured in the central annular depression 6 of the plate 5, by means of screws 15 is a metal plate 16 having a raceway 17 for the ball bearing 18. 60 The metal plate 16 and the wood plate 5 are provided with central registering apertures or openings 19 and 20, to receive a pivot pin 21 of the plate 22, which is secured by screws 23 to the lower part 24 of the 65 revoluble center piece 26 of the table, so that the center piece may revolve. Therefore, owing to the plate 5 resting upon the upper end of the central column 1, and being that the pivot pin 21 (which is carried 70 by the plate 22, which in turn is secured to the center piece 26) extends through the metal plate 16 and through the plate 5 and into the column, the table sections will rotate independently of the center piece and 75 vice versa. The annular plate 22 has a raceway 27 to receive the ball bearings 18, so that the center piece may revolve easily and with minimum friction. The center piece has an upper portion 28, and secured between the 80 upper and lower portions 24 and 28 of the center piece are divisional plates 29, forming compartments 30, for the reception of the drawers 31, which are slidable radially, which drawers are designed to carry napkins 85 and the like, and various eating utensils.

The various plates opposite the persons eating at this improved dining table are supported upon the extensible sections 10 and 14, whereas the various articles of food 90 are designed to rest upon the revolving center piece, that is, upon the upper part 28 thereof. When a person at one side of the table wishes an article of food upon the opposite side of the revoluble center piece, the 95 center piece is merely turned or revolved, until the desired article of food is opposite the person wishing the same. The bars 9 of the extension section 10 are braced by the transverse piece 33, whereas the bars 13 of 100 the extensible section 14 are braced by the angular pieces 34.

It will be observed that the extension pieces or sections 10 and 14 may be extended to any length desired, and suitable extension 105 boards such as shown at 35 may be inserted between the extension section, and held in the usual manner by the dowel pins 36.

The invention having been set forth, what is claimed as new and useful is:—

1. In combination, a standard or column having transverse wood plate arranged

thereon, said wood plate being provided with an annular depression, annular plate having a raceway on its upper surface and provided with a central aperture secured in said depression, said transverse wood plate having a central opening, a pair of extensible table sections having slideable connections consisting of tongue and groove bars, the bars of one table section having tongue and groove connections with the opposite ends of the transverse wood plate, a revoluble center piece having an annular plate provided with a pivot pin extending through the annular plate in said depression and through the transverse plate and into the column whereby the table sections may revolve independently of the center piece and vice versa, said annular plate and the center piece having a raceway, and antifrictional members in said raceways.

2. In combination, a standard or column, a revoluble center piece having pivotal con-

nctions with the upper end of the column, a transverse bar held on the upper end of the column by the pivotal connections, a 25 pair of extensible table sections mounted upon said bar below and adjacent the under face of the center piece, whereby said sections may be rotated as one body whether they are extended or closed, the central portions of the adjacent edges of the sections having recesses to receive a part of said pivotal connections when the sections are closed, the adjacent edges of the table sections adapted to receive insert extension 30 members, when the sections are extended.

In testimony whereof I have signed my name to this specification in the presence of two subscribing witnesses.

FRANK H. FRY.
